UNITED STATES PATENT OFFICE.

FRANK M. WAKIMOTO, OF HIGHLAND PARK, MICHIGAN.

RESILIENT SHOE LACE.

Application filed February 5, 1925. Serial No. 6,962.

To all whom it may concern:

Be it known that I, FRANK M. WAKIMOTO, a citizen of the United States, and resident of Highland Park, in the county of Wayne and State of Michigan, have invented new and useful Improvements in Resilient Shoe Laces, of which the following is a specification.

This invention relates to fasteners for 10 shoes, slippers, and the like, and has for its primary object the provision of a fastener that has substantially the same appearance as the familiar shoe lace now in general use and in addition will be resilient and permanently laced through all the eyelets of the 15 shoe.

The almost universal method of lacing shoes and the like by non-resilient laces threaded through eyelets on alternately opposite sides of the front opening has the 20 disadvantage of requiring the removal of the lace from the uppermost eyelets before the shoe can be removed from the foot. Often the lace must be withdrawn from a considerable number of eyelets before the shoe 25 can be freely removed, and, of course, after the shoe is again donned the lace must be again threaded through the upper eyelets before it is tied in place. This all requires 30 time, and occasions inconvenience to millions of people every day. An object of my invention is to obviate this waste of time and provide a shoe lace that will yield sufficiently to enable the removal of the shoes while 35 the lace remains in all of the eyelets, provisions being made for preventing the accidental slipping of the tips of the laces through the uppermost eyelets.

Other objects and advantages will be apparent from the following description, wherein reference is made to the accompanying drawings illustrating a preferred embodiment of my invention and wherein similar reference numerals designate similar 45 parts throughout the several views.

In the drawings:

Fig. 1 is a perspective view of a shoe equipped with my improved lace in the position assumed when the lace is tied.

Fig. 2 is a similar view of the shoe when the lace is untied and in position for permitting the removal of the shoe.

Fig. 3 is an enlarged detail view of the tip of my improved lace in the position it assumes when the lace is being stretched.

Fig. 4 is a similar view showing the posi-

tion assumed by the tip when the lace is being threaded through the eyelets, and

Fig. 5 is a detail section through the tip.

Referring now to the drawings, the numeral 5 designates a shoe of the ordinary or any desired construction having its upper portion separated at the front and provided adjacent each edge with a plurality of eyelets 6 for the reception of the lace 7. A tongue is secured behind the edge portions of the shoe upper to close the gap and prevent the eyelets from contacting the foot of the wearer.

My improved fastener 7 is preferably 70 formed of elastic material 7^a covered with fabric, thread or the like, as 7^b, to give the appearance of the ordinary shoe lace in general use. It is obviously possible for this covering 7^b to take the shape of a round, 75 flat or any desired shape. At each end of the lace 7 is secured a tip 8 comprising a cylindrical portion 8^a surrounding the extremity of the shoe lace and provided with a plurality of indentations or teeth 8^b to bite 80 into the lace covering to permanently secure the extremity of the lace within the tip. Each tip 8 is also provided with a rearwardly extending loop 8^c which projects beyond the rear extremity of the cylindrical 85 portion 8^a to engage against the exterior wall of the uppermost eyelet to prevent accidental passage of the tip 8 while the lace is being stretched, as during the removal of the shoe from the foot. The loop 8^c may 90 extend any desired distance from the rear of the cylindrical portion 8^a, and may be pressed into the body of the lace adjacent the tip when the tip is being passed through the eyelets during the lacing operation. To 95 strengthen the loop and to prevent it being bent away from the cylindrical portion of the tip, I preferably form the loop with an extension 8^d adapted to lie within the cylindrical portion of the tip and contact the 100 extremity of the lace where it is firmly secured by the indentations 8^b of the tip.

In operation, my improved fastener is 105 laced through the eyelets of the shoe in the ordinary manner utilized with the non-resilient laces in common use, each cross lace being pulled as tightly as desired and the projecting ends of the lace then tied into a bow, exactly as with the ordinary shoe lace. While so tied, the resiliency of the 110 lace permits the foot to move more freely than with the non-resilient laces, because the

- edges of the shoe upper may separate when pressure is brought against any portion thereof, as for example when the shoe bends while its wearer is walking or dancing.
- 5 When it is desired to remove the shoe from the foot, it is only necessary to untie the lace and slip the shoe off the foot. During the removal of the shoe after the lace is untied, the lace will first slip through the eyelets until the tip engages the uppermost eyelet, and thereafter the lace will stretch sufficiently to permit the removal of the shoe. When the tip of the lace reaches the uppermost eyelet, the projecting loop 15 8° engages one side of the eyelet while the cylindrical portion 8° of the tip engages the opposite side of the eyelet and additional pressure upon the lace will not pull the tip through the uppermost eyelet.
- 20 However, when it is desired to remove the lace from the shoe, it is only necessary to hold the tip so that the loop portion 8° first enters each eyelet, whereupon the remainder of the tip will pass through the eyelet in

the manner of the ordinary shoe lace tip. 25 While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claim. 30

Having described my invention, I claim:

A fastener for shoes equipped with eyelets comprising a resilient lace adapted to be threaded through the eyelets and carrying at each extremity a tip having a cylindrical portion adapted to be clamped upon the end of the lace and a loop portion in substantial alignment with the cylindrical portion but projecting beyond the clamped portion of the lace for the purposes described. 40

In witness whereof I hereunto set my hand. 45

FRANK M. WAKIMOTO.
